UNITED STATES PATENT OFFICE.

ELDA G. SMITH, OF SYRACUSE, NEW YORK, ASSIGNOR TO CROUSE-HINDS COMPANY, OF SYRACUSE, NEW YORK, A CORPORATION OF NEW YORK.

DROP-CORD ROSETTE.

Application filed September 20, 1923. Serial No. 663,922.

This invention has for its object what is commercially known as a drop cord rosette, which is particularly simple and strong in construction and in which the terminals are relieved of the supporting strain and the electrical connection between the terminals and the mechanical connection between the sections of the casing are made simultaneously upon successive endwise and partial rotary movement of the cap section.

The invention consists in the novel features and in the combinations and constructions hereinafter set forth and claimed.

In describing this invention, reference is had to the accompanying drawings in which like characters designate corresponding parts in all the views.

Figure 1 is an elevation of this drop cord rosette, the conduit outlet box being indicated in dotted lines.

Figure 2 is a vertical section on line 2—2 Fig. 1.

Figures 3 and 4 are face views of the base and cap sections and parts carried thereby.

Figure 5 is a plan view of the base section.

Figure 6 is an inverted plan view of the cap section.

This drop cord rosette comprises generally a case composed of a base section and a cap section having means for interlocking upon successive endwise and partial rotary movements of the cap section, terminal blocks carried by the sections, terminals carried by the blocks and arranged to interlock during such endwise and partial rotary movements of the cap section.

1 designates the base of the casing, which is formed with a circular opening. As here shown, this base section is constructed to be mounted upon an outlet box 2 having a circular opening in one side and is provided with screws 3, by means of which it is secured to the open side of box 2. The base section is thus annular or ring shaped in general form.

45 The base section is also formed with a cylindrical flange 4 skirting the opening in such section, this cylindrical flange having an out-turned lip or annular flange 5 formed with notches 6 therethrough, which are usually located diametrically opposite each other.

7 is the cap section. It is formed with a cup-shaped portion 8 and a central opening 9 for the outlet of the cord. The cup-shaped portion includes a cylindrical flange 10 which incloses the cylindrical flange 4 of the base

and butts against the base around the cylindrical flange 4, the cylindrical flange 10 having inwardly extending shoulders 11 for entering the notches 6 upon endwise movement of the cap and for interlocking behind the annular flange 5 upon the partial rotary movement of the cap and thus locking or mechanically securing the base and the cap together. The cap is detached from the base upon successive partial rotary and endwise movements of the cap.

12 is a terminal block mounted on the rear or upper side of the base 1 and having terminals 13, 14 on its inner face exposed through the opening inclosed by the cylindrical flange 4. The block 12 also has wire terminals or binding devices 15, 16 on its upper side to which the wires in the outlet box 2 are connected. This block is secured to the base 1 in any suitable manner as by screws 17 extending through holes or passages 17^a in the block and threading into holes in the base 1.

18 is a terminal block mounted in the cap and having terminals 19, 20 complementary to the terminals 13, 14 and arranged to interlock therewith upon successive endwise and partial rotary movements of the cap. These terminals 19, 20 are formed integral with binding devices 21, 22 to which the wires of the drop cord are connected, which wires extend through a central opening 23 in the block and out through the opening 9 in the cap. The cap is also formed with a hand hold or wings 24 on opposite sides of a hub 90 25 thereon and one-half or section 26 of this hub is removable and secured in place by screws 25^a, the section or half 26 being removable for the purpose of inserting wires or connecting them to wire terminals.

The terminals 13, 14 and 19, 20 are here shown as hook-shaped and formed with interlocking bosses and depressions arranged to coact snap catch fashion. Also springs 27, 28 are arranged beneath the terminals 13, 14 to press the terminals 19, 20 firmly in contact with the terminals 13, 14. Terminals 13, 14 and 19, 20 are spaced apart around the axis of the cap, are placed diametrically opposite each other and are arranged to interlock, or the terminals 19, 20 are arranged to hook under the terminals 13, 14 upon rotary movement of the cap and these terminals are so spaced apart as to come into interlocking relation upon endwise movement of the 110

cap when the shoulders 11 of the cap are passing through the notches 6 of the base.

In operation, the base 1 with its terminal block thereon is secured to the box, the connection between the wires in the box and the wire terminals 14 on the base having been first made. The cap 7 with the wires of the drop cord connected to the binding terminals 21, 22 is then placed on the base with the shoulders 11 passing through the notches 6 and with the terminals 19, 20 passing between the terminals 13, 14 of the base. The cap is then rotated carrying the shoulders 11 into interlocking engagement with the flange 5 of the base and carrying the terminals 19, 20 under the terminals 13, 14. The reverse of these movements detaches the cap from the base.

By the construction and the arrangement 20 of the cap and base and the terminals associated therewith, the electrical and mechanical connections are made at the same time by the small endwise movement of the cap and less than a quarter turn of the cap. 25 Hence, no tools are required to connect and disconnect the cap and the base. By this device, drop cord replacements can be made in a minimum time and, owing to the interlock between the sections of the casing, there is no

strain on the terminals and all current carrying parts are completely protected.

What I claim is:

A drop cord rosette comprising a casing 30 consisting of a ring-shaped base and a cap, the base having a cylindrical flange around 35 the opening thereof and an outturned annular flange at the end of the cylindrical flange, the annular flange being formed with notches therethrough, and the cap being formed with a cup-shaped portion to receive the cylindrical flange and with diametrically opposite shoulders for passing through the notches and interlocking with the annular flange upon successive endwise and partial rotary 40 movement of the cap, a terminal block 45 mounted on the base having hook-shaped terminals exposed to the opening in the base, and a terminal block on the cap having complementary hook-shaped terminals arranged to hook under the terminals associated with the base upon successive endwise and partial 50 rotary movements of the cap.

In testimony whereof, I have hereunto signed my name, at Syracuse, in the county of Onondaga, and State of New York, this 30th 55 day of June, 1923.

ELDA G. SMITH.
